UNITED STATES PATENT OFFICE.

FREDERICK W. COLE, OF NEWTON, MASSACHUSETTS, ASSIGNOR OF ONE-HALF TO MOSES G. CRANE, OF SAME PLACE.

REPEATER.

SPECIFICATION forming part of Letters Patent No. 449,574, dated March 31, 1891.

Application filed May 12, 1890. Serial No. 351,441. (No model.)

To all whom it may concern:

Be it known that I, FREDERICK W. COLE, of Newton, county of Middlesex, State of Massachusetts, have invented an Improvement 5 in Repeaters, of which the following description, in connection with the accompanying drawings, is a specification, like letters and figures on the drawings representing like parts.

10 My invention is embodied in a repeater for telegraphic signals of the kind which is used in connection with a number of circuits, each disconnected from the other, for the purpose of causing a message or signal that is transmitted over any one of said circuits to be automatically transmitted or repeated over all the other circuits connected with the repeating apparatus. An instrument of this kind is commonly employed in connection with fire-alarm telegraphic apparatus, so that a message or alarm turned in on any circuit is simultaneously transmitted or repeated over all the other circuits, and for convenience the apparatus will be hereinafter referred to as 15 forming part of a fire-alarm telegraphic apparatus in which the messages, signals, or alarms are originally transmitted in one circuit by a break-wheel and actuating mechanism for it, commonly called a "signal-box," and are repeated in the other circuits of the apparatus. 20

It is necessary for the proper operation of a repeating-instrument of this kind when a message is begun in one circuit, so that the repeater is thrown into operation to repeat 25 that message over the other circuits, that the entire apparatus should remain under control of the circuit in which the message is started until that message is completed, so that if a message or alarm should be subsequently 30 turned in upon any other circuit before the first one is completed there will be no interference, and it is furthermore necessary that the circuit in which the alarm is first started should remain under control of the break-wheel or point external to the repeater, so 35 that although the repeater breaks and closes all the other circuits it must retain the one circuit in which the message is started closed at the repeater-station, so that it will be in 40 control of the break-wheel of the signal-box or transmitting-station. These results have

usually been attained by employing a mechanical motor to break all the circuits at each break in the circuit that is receiving the message, the operation of said motor depending upon relays or electro-magnets in each of the circuits, and means have been provided by which the relay which has been first operated will retain control of the motor, while all the other relays will be immediately affected by the movement of the motor itself and have their armatures locked in some way so as to render them inoperative so far as affecting the motor is concerned as long as the motor remains under control of the circuit 55 first operated. In the greater number of repeaters that have been heretofore devised this locking of the relay-armatures has been effected mechanically by the movement of the motor itself, and in another application, Serial No. 319,739, filed by me August 5, 1889, I have shown and described a repeater in which the locking of the armatures is effected by other electro-magnets, which are, however, connected with and effected by the currents 60 passing through the main circuits of the relays themselves, such apparatus depending upon the relative speed of movement of the two armatures, both of which respond to the same change in current in the circuit with 65 which both are connected.

The present invention consists, mainly, in novel means for controlling the armatures of the relays in the main circuits, said armatures being controlled by locking devices operated by other electro-magnets which are not, however, in the main circuits with the relays. The main relays control a motor mechanism which makes one operation at each vibration of one of the main-relay armatures and in said operation affects the circuits of all the other relays, and thereby causes the message to be repeated in all the other circuits impulse by impulse, corresponding to the impulses or circuit changes 70 in the circuit originally operated, which controls the motor. The said motor also controls a local circuit, including the governing-magnets of all the relays, said local circuit being changed at the first operation of the motor— 75 for example, being opened and remaining so until the circuit first operated is restored to

its normal condition at the completion of the message. The circuit of the controlling-magnets is changed after the relay first operated has responded to the change in its circuit, but 5 before the relays in the other circuits have responded to the change produced by the motor of the repeater, and the mechanical connections between the main-relay armatures and the armatures of the governing-magnets 10 is such that when the governing-magnets are operated first they lock the main-relay armatures in attracted position; but if the main-relay armatures have been retracted before the corresponding governing-magnet is de- 15 magnetized the latter will not interfere with the subsequent movements of the main-relay armature. Appliances are also provided for restoring the repeater to normal condition in case one of the main circuits is deranged or 20 broken, so that the said instrument may operate properly with the other circuits which are in working condition.

Figure 1 is a side elevation of a motor by which the signals or breaks made in one main 25 circuit are repeated in the other main circuits; Fig. 2, a side elevation of one of the main relays and its controlling-magnet and the co-operating parts; Fig. 3, a side elevation of another of said main relays with its controlling- 30 magnet and co-operating parts as seen from the opposite side to that represented in Fig. 2; Fig. 4, a detail of the contacts controlled by the main-relay armature, also showing some of the other devices that co-operate 35 with the main-relay armature, as will be hereinafter described. In Figs. 1, 2, 3, and 4 portions of the several circuits are indicated in diagram; Fig. 5, a plan view of the motor shown in Fig. 1; Figs. 6 and 7, details of portions of said motor on a larger scale, the parts being shown in Fig. 7 as viewed from the opposite side of the instrument to that seen in Fig. 1. Figs. 8 and 9 are enlarged details of 40 an adjustable contact constituting one member of a circuit-closer such as operated by the instrument shown in Fig. 1; Fig. 10, a diagram representing the several circuits and electro-magnets and circuit-controllers therein; Fig. 11, an enlarged detail of the co-operating device of the main and governing magnet armatures as seen in elevation, looking 45 toward the poles of the main-relay magnet; Fig. 12, a detail showing the said device in side elevation; Figs. 13 and 14, sectional details showing the parts represented in Fig. 11 mainly in side elevation, as seen looking toward the right in Fig. 11, and illustrating the operation of the several parts.

The main-relay magnets a , one for each 50 circuit, are included in independent main circuits containing signal-boxes or circuit-breaking devices, such as indicated in diagram at b , Figs. 1 and 10, said main circuit connecting, as shown at 2, with one terminal of the relay- 55 magnet, the other terminal of which is connected, as shown by wire 3, with one member of a circuit-closer c , the other member of

which is connected with the other terminal 4 of the main circuit, as shown in Figs. 1, 3, and 10. The members of the circuit-closers c are connected with cross-pieces $c^2 c^3$, supported on the frame of the motor shown in Fig. 1, there being one of said circuit-closers for each of said main magnets, and the frame-piece c^3 being connected with a rock-shaft, 75 which is rocked at each operation of the motor sufficiently to bring the members of all the circuit-closers in contact and then separate them, the frame-piece c^3 being operated by an arm c^4 , (see Figs. 5, 6, and 7,) engaged by 80 an eccentric-pin c^5 on an arbor c^6 , provided with a detent-arm c^7 , (see Fig. 1,) controlled by a detent-lever c^8 , that is operated by the armature of a magnet c^9 , which controls the motor, and is controlled by the relays a , as 85 will be hereinafter explained. The shaft c^6 is impelled by any suitable train of wheel-work, herein called the "motor," the main shaft, to which the power is primarily applied by a weight or spring, being shown at e , Fig. 90 1, and the said shaft c^6 being provided with a fan or governor e^2 to prevent too sudden movement of the shaft and too great shock of the detent when it is arrested after each rotation of the said shaft c^6 . The detent is 95 engaged and the motor is arrested when the eccentric c^5 is in such position as to keep the circuit-closers c open, as shown in Figs. 1 and 5, and in order that the main circuit 2 3 4 may not be normally open the said wires 3 100 and 4, leading to the two members of the circuit-closers c , are respectively connected by wires 5 and 6, Fig. 10, with two members of a normally-closed circuit-closer f , supported on the frame-work of the relay-magnet, as 105 best shown in Figs. 3 and 12. In Fig. 3 wire 3 connects directly with f . It will thus be seen that the circuit-closer c can affect or control the main circuit only when the circuit-closer f is open. 110

The detent $c^7 c^8$ for the motor is disengaged and the shaft c^6 permitted to make one rotation at each operation of one of the relays a by the following devices, (best shown in Figs. 1, 2, and 4:) The armature-lever a^2 of each 115 relay is provided with a contact-spring a^3 , which when the said armature is attracted makes contact with the stationary contact a^4 , and the said pairs of contacts or circuit-closers $a^3 a^4$ of the several relays are connected 120 in series in the local circuit 7 8 9 10, including the controlling or detent-operating magnet c^9 of the motor, as shown in Figs. 1, 2, and 4, in which Fig. 4 represents the armature-lever of another relay than the one represented 125 in Fig. 2. When all the relay-armatures are attracted or are retained in attracted position by the attraction of their magnets or otherwise, the said circuit-closers $a^3 a^4$ are all closed and the circuit of the magnet c^9 is complete, 130 the said magnet is energized, and the motor-detent is retained engaged. If any one of the armatures of the main relays a is retracted, it opens the said local circuit, demagnetizes the

magnet c^9 , and permits the shaft c^6 to make one rotation.

The detent-arm c^8 is provided with double stop-points, so as to arrest the detent-arm c^7 when the said arm c^8 is in either position, and if it arrests the arm c^7 in the position assumed when the magnet c^9 is demagnetized the subsequent energizing of the said magnet will move the arm c^8 , so that the detent c^7 will escape from the first stop-pin and be arrested on the second without a movement sufficient to affect the parts operated by the shaft c^6 , and consequently it will be understood that the said shaft c^6 will be released and make a complete rotary movement at each complete to-and-fro movement of any one of the armatures of the main relays a . Thus, if the main circuit of any one of the relays a is broken and closed at definite intervals, as by the break-wheel b , (see Fig. 1,) the magnet c^9 will be correspondingly affected and the shaft c^6 will make complete rotations at each such break and closure of said main circuit, said shaft producing movements by which the circuit-closers c are closed and opened for a length of time about equal to the time that a circuit is closed between the successive breaks produced by a break-wheel b . In order that this operation of the circuit-closers c should produce the desired effect of closing and opening the main circuits, it is necessary that the circuit-closers f of those circuits which are to be controlled by the circuit-closers c should be opened; but it will not do to have the circuit-closer f corresponding to the relay which is first operated opened, for if it were the said circuit would be completely opened both at c and f as soon as the motor-shaft had made one complete rotation, and consequently the break-wheel b could produce no further effect in said circuit. It is therefore necessary for the proper operation—that is, in order that the relay first operated should remain under control of the break-wheel and that the other relays or circuits should remain under control of the circuit-closers c of the motor—that the circuit-closer f of the relay that first operated should remain closed and that the circuit-closers f of all other relays should be opened to place their circuits under control of the circuit-closers c . This result is accomplished by the governing-magnets k , one of which is supported on the frame-work of each relay in definite mechanical relation to the relay-magnet a and its armature, as shown in Figs. 2 and 3. The armature-levers of said controlling-magnets are pivoted at k^2 , and have extended arms k^3 , the ends of which overhang the armature-levers a^2 of the relays, and are provided with pendent pieces k^4 , the lower ends of which hang at the rear of projections k^5 , carried by the main armature-levers, in such manner that when the main armature-levers are retracted they swing the arms k^4 outward a short distance, as represented in dotted lines, Fig. 14. The said pendent k^4 is provided with a pin or projection k^6 , that normally stands

above one member of the circuit-closer f in such position that if the said pendent k^4 is dropped by the retraction of the armature of the magnet k when said pendent is in its most forward position—that is, when the main armature-lever is attracted—the said projection k^6 will strike on the lower contact-spring of the circuit-closer f and separate it from the upper spring of the said circuit-closer, (see Fig. 12,) thereby opening the same, and thus leaving the corresponding main circuit in control of the circuit-closer c , which is operated by the motor. If, on the other hand, the pendent k^4 should be swung outward to dotted-line position, Fig. 14, before it is dropped by the retraction of the armature by the corresponding governing-magnet, the pin k^6 will not engage the spring of the corresponding circuit-closer f , and the latter will remain closed, so that the circuit-closer c of the corresponding circuit can produce no effect thereon.

The governing-magnets k are all connected in series with one another in a local circuit 15 16 17, (see Figs. 1, 2, 3, and 10,) controlled by a circuit-closer m , (see Fig. 1,) governed by the motor, as will be described, and are consequently all operated simultaneously, and their operation depends upon and follows the operation of the motor when released by the magnet c^9 . Consequently, as the operation of the magnet c^9 depends upon the retraction of the armature of the relay a first operated, it follows that the pendent k^4 for the governing-magnet corresponding to said relay will be swung back, and when the governing-magnet is demagnetized it will fall without opening the corresponding circuit-closer f , so that the corresponding main circuit will remain closed at the repeater, and will thus remain under control of the break-wheel at the external transmitting-station.

The construction of the motor is such that the circuit-closer m is opened before the circuit-closers c are opened toward the end of the rotation of the shaft c^6 , so that the pendants k^4 will be dropped while the armatures of the other relays than the one which is responding to a signal are in their closed position, and will consequently open the circuit-closers f corresponding to all said relays, leaving them in control of the circuit-closers c , that are operated by the motor, and thus so long as the circuit of the magnets k remains open the relay first operated will remain under control of its external transmitter, and all other circuits will remain under control of their circuit-closers c and will be closed and broken at each forward and backward movement of the armature of the first relay corresponding to the passage of a tooth of its break-wheel, or, in other words, will repeat, impulse by impulse, the impulses of the message that is being transmitted by the break-wheel in the circuit first operated.

If the armatures of the relays that are controlled by the circuit-closers c were permitted

to respond to the circuit changes produced by said circuit-closers, they would open the circuit 7 8 9 10 of the motor-controlling magnet c^9 , which would thus be taken out of control of the relay that was responding to an external transmitter. In order to prevent this from happening, the relay-armatures that are under control of the motor are mechanically locked in their attracted position during the operation of the motor by the action of the controlling-magnets, the armatures of which are retracted, as before stated, before the main relay-armatures respond to a break. This locking is effected by a lock n , (see Figs. 4, 13, and 14,) shown as a hook pivoted at n^3 on a block carried by the stationary frame-arm a^{10} of the relay and having its hooked end in position to engage with a projection n^2 on the armature-lever. The said hook is, however, weighted, so as to normally keep its hooked end resting above the projection n^2 , so that the latter will only be engaged if the hooked end of the lock is depressed. The said hooked end is under a projection n^4 of the pendent arm k^4 of the governing-magnet in such position that if the latter is in its normal position (shown in full lines, Fig. 14) the said projection n^4 will engage the hooked end of the lock upon the descent of said pendent k^4 when the governing-magnet is demagnetized, thus throwing the hook into engagement with the projection n^2 on the main relay-armature and preventing the latter from being retracted if the relay is subsequently demagnetized. Thus if the governing-magnet is demagnetized before the relay-armature the latter will be locked. (See dotted lines, Fig. 13.) The movement of the pendent k^4 from the full to the dotted line position, Fig. 14, which takes place if the relay-armature is retracted before the governing-magnet armature, carries the projection n^4 beyond the range of the end of the hook, so that in case the relay-armature is retracted first, as takes place in the circuit in which the message is originally transmitted, the lock will not be operated. Consequently the relay-armature will be left free to respond to its signal.

The devices thus far described are all that are necessary for the proper reception of the message on one circuit and its repetition over the other circuits; but it will be seen that with the contrivances thus far described if one main line should become permanently broken or the current removed from it in some manner its relay-armature would fall back and cause a single operation of the motor, which would release all the governing-magnets, thus causing the circuit-closers f of all the circuits other than the one in which the break occurred to be opened, and as the motor will come to rest with the circuit-closers c open all the lines will be opened and disabled, and to prevent this result from taking place, or, in other words, to restore the parts other than the broken line to working condition, other devices are used, the construction and

operation of which will now be described, it being understood that their object is mainly to place and keep the repeater in working condition for all other lines in case one or more of the lines is accidentally broken or deranged. 70

It is first necessary to describe the means for operating the circuit-closer m , that controls the governing-magnets k , these parts 75 being best shown in Figs. 6 and 7. The said circuit-closer m is normally kept closed by the pressure of an arm m^2 , loosely pivoted on an arbor m^3 of a secondary motor comprising a train $o o^2 o^3 o^4 o^5 o^6$, (see Figs. 1 and 5,) 80 which is independent of the train that drives the detent-shaft c^6 , which has been before described, said secondary train having an escape-wheel o^7 and vibrating pallets o^8 , constituting a governor to give it a time-movement. 85 The arm m^2 , that operates the circuit-closer m , is, as before stated, loose on a shaft m^3 , and is acted upon by a spring m^4 , (see Fig. 7,) tending to turn it away from the circuit-closer m , so as to permit the members of said circuit-closer to spring apart and open the circuit 15 90 16 17 of the governing-magnets. The arm m^2 is, however, normally prevented from moving under the action of its spring m^4 by a pawl m^5 , having a projection m^6 , that lies under a tripping-arm m^7 , connected with the rock-shaft d , that carries the cross-bar c^3 of the main circuit-closers c . Thus at the first operation of the main-motor-controlling magnet c^9 and consequent rotation of the shaft c^6 the arm m^7 is vibrated, together with the arm c^4 and frame c^3 , in such direction as to trip the pawl m^5 or disengage it from the teeth of a ratchet m^8 , which is connected with the shaft m^3 of the secondary motor. When 105 the pawl m^5 is so tripped, the spring m^4 throws the arm m^2 back out of engagement with the circuit-closer m , as shown in dotted lines, Fig. 6, permitting the latter to open, and thus open the circuit of the governing-magnets k , 110 as before stated. The said arm m^2 is connected with another arm m^9 , which engages the escape-wheel o^7 , as shown in Fig. 6, and thus constitutes a detent or stop that arrests the secondary train when the arm m^2 is in 115 normal position, closing the circuit-closer m ; but when the arm m^2 is released by the tripping-arm m^7 , as just described, the arm m^9 disengages the escape-wheel and the secondary motor begins to run, turning the ratchet 120 m^8 in the direction that would carry the arm m^2 back into engagement with the circuit-closer m if said arm m^2 were connected with said ratchet m^8 . When the tripping-arm m^7 comes back to its normal position at the end of 125 the rotation of the detent-shaft of the main motor, the pawl m^5 engages the ratchet m^8 , which then begins to turn the arm m^2 back toward its original position with a definite time rate 130 of movement, and the distance that the arm m^2 moves from the circuit-breaker and the speed of the secondary train and the ratchet m^8 in turning it back again are such that the time required to carry the arm m^2 back to the cir-

cuit-closer is greater than any interval which occurs between successive current changes in the normal transmission of a signal in one of the main-line circuits. The trip-arm m^7 is 5 curved, as best shown in Figs. 6 and 7, so that it trips the pawl m^5 in whatever position the latter may be with relation to the trip-arm, and consequently at every operation of the main detent-shaft the pawl is tripped and 10 the arm m^2 thrown back by its spring m^4 to its position most remote from the circuit-breaker m , and when the main motor comes to rest it immediately begins to travel again toward the circuit-closer m . By this construction 15 it will be seen that so long as the main motor is intermittently operated in response to a signal received on one of the main lines the arm m^2 will never reach and close the circuit-closer m , and consequently 20 the governing-magnets will remain demagnetized during the entire transmission of a signal; but if one of the main circuits should remain open for an indefinite period of time the main motor will be arrested, the trip-arm 25 m^7 will not act on the pawl m^5 , and the latter will remain in engagement with the ratchet m^8 until the said ratchet has carried the arms m^2 m^9 around to normal position, closing the circuit-closer m , and finally arresting the secondary motor by the engagement of m^9 with o^7 . This closing of the circuit-closer m and 30 circuit of the governing-magnet which thus takes place after an interval of time slightly greater than the longest interval between the two successive strokes of a normal message or signal causes all the governing-magnets to 35 be energized and thus to raise the pendants k^4 , which act releases the armatures of the main relays by permitting the disengagement of the lock n n^2 , and also closes their 40 circuits at f , leaving them under control of their external transmitters. The relay that is in the deranged circuit will, however, have its armature still remain retracted, and as it 45 was not locked in attracted position the raising of the pendant k^4 by its governing-magnet will not restore it, and consequently the local circuit 7, 8, 9, and 10 of the governing-magnet c^9 of the motor would remain open at 50 a^3 a^4 , thus preventing any of the other relays from controlling the motor unless means were provided for closing the said local circuit at the disabled relay. This is done by the devices best shown in Fig. 4, consisting 55 of a switch-arm r , pivoted on the side of the armature-lever and connected with the stationary contact a^4 , as shown by wire 11, Figs. 4 and 13, the said switch-arm r being the part that carries the projection k^5 , before 60 mentioned, that throws the pendant-arm k^4 back when the main relay is retracted before the governing-magnet armature. The said pendant k^4 is recessed, as shown at k^{40} , Fig. 14, forming a shoulder that drops below the 65 projection k^5 when the governing-magnet armature is retracted, and if the said governing-magnet armature is attracted while the main-

relay armature remains in retracted position, said shoulder will engage the projection k^5 and will turn the switch-arm r , bringing it up into 70 engagement with a projection a^{30} from the local-circuit contact a^3 , carried by the main-relay armature, thus connecting a^3 and r and making a connection through r and 12 over the break between a^3 and a^4 in the local circuit at the disabled relay, thus closing the 75 said local circuit and leaving it in condition to respond to the action of the contacts a^3 a^4 of any of the relays that are in proper working condition, as before described. The elasticity of the contact-spring a^3 holds its upper end forward slightly with relation to the armature-lever, thus pressing the contact a^{30} against the switch-arm r sufficiently to retain 80 the said switch-arm in contact with it; but said switch-arm gravitates freely upon its pivot, and consequently if the disabled main circuit is repaired externally the main-relay armature will be attracted, and when the end of the spring-contact a^3 comes against the stationary contact a^4 it will be sprung back 85 slightly with relation to the armature-lever, which will be sufficient to relieve the pressure on the switch-arm r , which will then drop by gravity to its normal position, so that everything 90 will be restored to its normal working condition at the repeater automatically as soon as the line is placed in working condition external to the repeater. 95

The relations of circuits and mode of operation have been described fully in describing the construction of the parts; but it may be convenient to state, briefly, the several steps in the operation, which are as follows: First, assuming that all the main lines are closed 100 and the main and secondary motors are both stopped in normal position, the current in one main circuit—for example, that represented in Figs. 1 and 3—will pass through the main relay a and the several break-wheels or transmitters b as follows: from the main battery by wire 2 to one terminal of the relay-magnet, thence from the other terminal of the relay-magnet by wires 3 and 5 to the circuit-closer f , thence by wire 6 to the main line 4, 105 which extends around to the other terminal of the main battery. The said circuit is broken by the action of the break-wheel. The relay-armature falls back and breaks at a^3 a^4 . The local circuit 7 8 9 10 of the motor-controlling magnet c^9 thus permits the 110 detent-shaft for the main motor to make one revolution, in which the tripping-arm m^7 operates to release the arm m^5 , which permits the circuit-closer m to open, demagnetizing 115 the governing-magnets k and permitting their pendants k^4 to drop. The pendant k^4 will be in dotted-line position, Fig. 14, for the relay which has just been operated, and will produce no effect at that relay. On all 120 the other relays it will be in full-line position, Fig. 14, and in dropping will open the circuit-closers f , and also depressing the locking devices n into engagement with the pro-

jections n^2 , thus locking the relay-armatures in attracted position. (See dotted lines, Figs. 12 and 13. While this has been going on the circuit-closers c have all been closed, the timing being such that they are closed just before the circuit-breakers f are opened, as just stated, and as the detent-shaft continues its rotation the said circuit-closers c are again opened, thus producing a break in all the circuits other than the one first operated by its break-wheel. As said break-wheel continues to operate, the relay-armature in its circuit will move to and fro and at each to-and-fro movement will let the detent-shaft and main motor make one rotation, thus closing and breaking the circuit-closers c , and thereby repeating the closure and break of the break-wheel into the other circuits. The arm m^2 will during this operation be traveling back and forth toward but never reaching the circuit-closer m until, finally, after the message of the break-wheel and the relay-armature which responds to it has come to rest, the main motor will no longer be operated, the pawl m^5 will not be tripped, and the secondary motor will carry the arm m^2 around, so as to close the local circuit 15 16 17 of the governing-magnets, which will then be attracted, permitting the circuit-closers f to close and the main armature-locks n to disengage the armatures, thus restoring all lines to normal working condition. If the main-relay armature which first operated had, however, come to rest in retracted position, as by an accidental rupture or disengagement of the line, the operation would be in all respects the same as before, except that at this relay the governing-magnet would be energized while the main-relay armature was retracted, and the governing-magnet armature in such operation would close the switch $r a^30$, thus closing the local circuit of the motor-governing magnet c^9 , so that it would be ready to respond to the action of the other relays. It will be seen that the controlling arm or member m^2 of the circuit-changer that controls the circuit of the governing-magnets is movable quickly in one direction—namely, to open the said circuit-closer—and slowly in the opposite direction, so that it requires a definite time interval for said member to restore the circuit-changer to its normal condition. The locking device n for the main relay armatures, although at times engaged and moved by the armatures of the governing-magnets, is otherwise independent of said governing-magnets—a construction having important advantages over that in which the main armatures are locked by the direct action of armatures of governing-magnets or by a locking device connected directly with the armatures of governing-magnets.

It is desirable in apparatus of this kind that the contact-points of a circuit-closer—such, for example, as the one c or the one a^3 a^4 —should be capable of minute adjustment with relation to one another, and in order to

attain this result one of the said contacts (the one that is stationary in the operation of opening and closing the circuit) is made, as shown in Figs. 8 and 9, consisting of a screw c^20 , the point of which constitutes the anvil against which the other member, usually a spring or yielding piece, is pressed in closing the circuit. The end of said screw may be adjusted with relation to the co-operating member of the circuit-closer by turning the said screw in its socket, in which it should have a somewhat close fit, and in order to provide for such adjustment without disturbing the connection between the said contact-piece c^20 and the wire or conductor of which it forms a terminal its threaded portion is engaged by a forked spring-plate c^21 , the prongs of which spring sufficiently to accommodate themselves between the threads of the screw c^20 . The circuit-wire, as 3, is connected with the spring-plate c^21 , which maintains an electrical connection with the screw c^20 while providing for the turning of said screw to adjust its position, as before described, and it will be seen that the contact between the plate c^21 and screw c^20 is not varied by any amount of longitudinal movement of the screw that can take place in adjusting it. 95

I claim—

1. In a repeater, the combination of two or more main relays, each in a separate main circuit, armatures therefor, a locking device for each armature, and a governing electro-magnet for each locking device with a circuit-changer for the circuit of said governing electro-magnets and a controlling member therefor movable quickly in one direction and slowly in the other direction, substantially as described. 105

2. In a repeater, the combination of two or more relays, each in a separate main circuit, and armatures therefor, a motor and detent therefor controlled by the armatures of said relays, with a governing-magnet for each main relay and a circuit for the governing-magnets, a circuit-changer in said circuit, and a controlling member therefor movable quickly in one direction and slowly in the other direction, substantially as described. 115

3. In a repeater, the combination of two or more main relays, each in a separate main circuit, and armatures therefor, with governing-magnets for said main relays and a circuit for said governing-magnets, and circuit-changer therein, and a timed controlling member for said circuit-changer, whereby the circuit of said governing-magnets may be held in an abnormal condition a longer time than the longest change in the main circuit produced in transmitting a signal, substantially as described. 125

4. In a repeater, the combination of two or more main relays, each in a separate main circuit, with governing-magnets for said relays, armatures for said relays and magnets, and a locking device for each main-relay armature moved by but made independent of the 135

armature of said governing-magnet, substantially as described.

5. In a repeater, a main-relay magnet, its armature, and a circuit-controlling contact operated by it, combined with a governing-magnet and its armature and a switch, both members of which are connected with the main-relay armature and accompany its movements without relative change, and one of 10 the two members of which is moved with relation to the other by the governing-magnet armature, substantially as described.

6. In a repeater, two or more main-relay magnets, each in a separate main circuit, a 15 governing-magnet for each main-relay magnet, a circuit for said governing-magnets, a circuit-controller therefor, a motor and detent therefor, and an electro-magnet for said detent, and a local circuit for said electro-magnet, combined with two circuit-controllers for said local circuit, one of which is controlled by the main-relay magnet and the other by the governing-magnet, substantially as described.

25 7. In a repeater, the combination of two or more main-relay magnets, each in a separate main circuit, with a governing-magnet for each main-relay magnet, a locking-lever operated by each governing-magnet, a circuit for 30 said governing-magnet, and a timed circuit-controller in said circuit to maintain it in its abnormal condition for a predetermined length of time, substantially as described.

8. In a repeater, the combination of two or 35 more main relays, each in a separate main circuit, with governing-magnets for said relays, armatures for said relay-magnets, and a locking device for each main-relay armature moved by but made independent of the armature of said governing-magnet, and a circuit-controller in each main circuit controlled by the armatures of the governing-magnets, substantially as described.

9. In a repeater, the combination of two or 45 more main-relay magnets, each in a separate main circuit, and a governing-magnet for each main-relay magnet, combined with two circuit-controllers in each main circuit, one of which, as *c*, is controlled by the main-relay magnet, the other of which is controlled by the governing-magnets, substantially as described.

10. In a repeater, the combination of two or more main-relay magnets, each in a separate main circuit, with circuit-controllers, as *c*, in said main circuits controlled by said main-relay magnets, a governing-magnet for each main-relay magnet, and circuit-controllers, as *f*, in each main circuit controlled, respectively, by the co-operation of the corresponding main-relay and governing magnet, substantially as described.

11. A telegraphic repeater apparatus comprising two or more main-relay magnets in 55 main circuits disconnected from one another, a local circuit governed by the armatures of said relay-magnets, and a detent and control-

ling-magnet therefor in said local circuit, combined with a motor governed by said detents and circuit-closers, one for each main circuit, 70 operated by said motor at each movement permitted by the detent-controlling magnet, a number of governing-magnets, one to each main relay, and a circuit for said governing-magnets controlled by said motor, substantially 75 as described.

12. The combination of a main-relay magnet and armature with a governing-magnet and armature included in a separate circuit from said main-relay, and a movable lock for 80 said main-relay armature disconnected from but adapted to be engaged and operated by a movable engaging part connected with said governing-magnet armature, whereby the said main-relay armature is locked in normal 85 position if the circuit of the governing-magnet is changed from normal condition before that of the corresponding main relay is so changed, said engaging part of the governing-magnet armature being in position to be acted 90 upon by the main-relay armature, so as not to operate the lock if the main-relay armature is changed from normal position before the governing-magnet armature is so changed, substantially as described. 95

13. The main-line circuit and two independently-operating circuit-controllers, as *f* and *c*, each having one member connected with one terminal of said main circuit and its other member connected with the other terminal of said main circuit, and the main-relay magnet included in said circuit, combined with a governing-magnet and armature provided with a movable engaging device co-operating with one only of said circuit-controllers, the said engaging device being operated by the main-relay armature to shift it from the position to act upon said circuit-controller, substantially as described. 100 105

14. The main-relay magnet and armature and circuit-controlling contact operated by the latter constituting one member of a circuit-controller, combined with a governing-magnet and armature, and an independently-operating switch adapted to afford electrical 110 connection between the members of said circuit-controller when not in contact with one another, and a switch-actuator operatively connected with the said governing-magnet armature, whereby said switch may be operated to close the circuit controlled by the main-relay armature independently of the latter, substantially as described. 115 120

15. The combination of two or more main relays in main circuits disconnected from one another, a motor and detent therefor controlled by the armature of said relays, a number of governing-magnets, one to each relay, and circuit therefor, and a circuit-closer in 125 said circuit and motor for operating the same governed by the detent mechanism of the first-mentioned motor, substantially as described. 130

16. The combination of the main-relay mag-

net and armature with a governing-magnet and armature therefor, a pendant connected with said governing-magnet armature, but being independently movable thereon and adapted to 5 be engaged by the main-relay armature, and a lock for said main-relay armature engaged by said pendant when the governing-magnet armature is moved while the main-relay armature remains in normal position, substantially 10 as described.

17. The combination of the main-relay magnet and armature with a governing-magnet and armature therefor, a pendant connected with said governing-magnet armature engaged by the main-relay armature, and a circuit-closer in the main-relay circuit engaged by the said pendant when the governing-magnet armature is moved while the main-relay armature is in normal position, but not 15 otherwise, substantially as described.

18. The combination of the main-relay magnet and armature with a governing-magnet and armature therefor, a pendant connected with said governing-magnet armature engaged by the main-relay armature, and a 20 switch engaged by said pendant when the

governing-magnet armature is moved while the main-relay armature is in abnormal position, substantially as described.

19. The combination of the contact-carrier, 30 as c^3 , with an actuating-motor and detent therefor, and an eccentric rotated by said motor when its detent is released, and connections between said eccentric and contact-carrier, whereby the latter is vibrated at each 35 movement of the motor, substantially as described.

20. The combination of a contact-screw, as c^{20} , forming one member of a circuit-closer, with a forked spring-plate, the prongs of 40 which engage with said screw in the threads thereof, thereby maintaining electrical contact with said screw while permitting the same to be adjusted longitudinally, substantially as described.

In testimony whereof I have signed my name to this specification in the presence of two subscribing witnesses.

FREDERICK W. COLE.
